TUBE RACK FOR A MEDICINE CABINET

Margaret Ann Krikker, 164 Colonial Ave.,
Albany, N.Y. 12208

Filed Sept. 9, 1968, Ser. No. 13,454

Term of patent 14 years

Int. Cl. D6—01
U.S. Cl. D33—16

FIG. 1

FIG. 2

FIG. 4

FIG. 3

FIG. 5

FIG. 1 is a front elevational view of a tube rack of a medicine cabinet embodying my new design;

FIG. 2 is an elevational view taken from one side thereof;

FIG. 3 is an elevational view taken from the side opposite that shown in FIG. 2;

FIG. 4 is a top plan view thereof; and

FIG. 5 is a perspective view thereof.

I claim:

The ornamental design for a tube rack for a medicine cabinet, as shown.
